UNITED STATES PATENT OFFICE.

CHARLES H. NUMAN, OF NEW YORK, N. Y.

DESIGN FOR AN INKSTAND.

No. 39,268.

Specification for Design.

Patented April 21, 1908.

Application filed February 21, 1908. Serial No. 417,203. Term of patent 7 years.

To all whom it may concern:

Be it known that I, CHARLES H. NUMAN, a citizen of the United States, residing at New York city, in the county and State of New York, have invented a new, original, and ornamental Design for an Inkstand, of which the following is a specification, reference being had to the accompanying drawings, forming a part thereof, and in which—

Figure 1 is a perspective view; Fig. 2 a top view, and Fig. 3 a side elevation of an ink-

stand bearing and incorporating my design, Fig. 1 having been taken, for clearness of illustration, from the rear end of the inkstand.

I claim:

The ornamental design for an inkstand, as shown.

CHARLES H. NUMAN.
